UNITED STATES PATENT OFFICE.

STEPHEN SIMON AND WILLIAM O'NEILL, OF NEW HAVEN, CONNECTICUT.

CURTAIN FIXTURE.

1,407,823.

Specification of Letters Patent. Patented Feb. 28, 1922.

Application filed May 31, 1921. Serial No. 473,757.

To all whom it may concern:

Be it known that we, STEPHEN SIMON and WILLIAM O'NEILL, citizens of the United States, residing at New Haven, in the county 5 of New Haven and State of Connecticut, have invented a new and useful Improvement in Curtain Fixtures; and we do hereby declare the following, when taken in connection with the accompanying drawings, and 10 the characters of reference marked thereon, to be a full, clear, and exact description of the same, and which said drawings constitute part of this application, and represent, in—

15 Fig. 1 a face view of a curtain fixture constructed in accordance with our invention.

Fig. 2 a side view of the same.

Fig. 3 a top or plan view of the same.

This invention relates to improvement in 20 curtain fixtures, or supports for window shades or curtain poles, or both, and particularly to devices which are secured in place without the use of nails or screws, the object being to provide a simple arrangement of 25 parts which is adjustable and which is easily secured in position and readily removable, and the invention consists in the construction as hereinafter described and particularly recited in the claim.

30 In carrying out our invention, we employ a top-bracket 5, comprising a flange 6 adapted to set over the upper edge of a window casing 7. This bracket extends downward over the face of the casing and is formed 35 with flanges 8 and 9, each formed with vertically-arranged slots 10 through which an arm 11 extends, these arms being provided with openings 12 for the reception of the ends of a window shade roller fixture, and 40 with a forked end 13 to support a curtain rod. Resting upon the arm 11, between the flanges 8 and 9, is a hook 14 at one end of a chain 15, the other end being coupled with

a latch 16 provided, on opposite sides, with lugs 17 for engagement with notches 18 45 formed in the flanges 19 of a bottom-bracket 20, which has an inwardly-projecting finger 21 to engage with the lower edge of the casing 7.

It will be understood that these are arranged for the right- and left-hand sides of 50 the window.

To adjust the device, the arm 11 is passed through the flanges 8 and 9 of the top-bracket and the hook 14 engaged therewith. 55 The latch 16 is then engaged with the bottom-bracket by having the lugs 17 engage with the notches 18, after which the latch is turned downward, as shown in Figure 2 of the drawings, so as to place the chain under tension and clamp the two brackets onto 60 the window casing.

With this construction the arms 11 are adjusted to accommodate shade rollers of different lengths; the device is applied without 65 screws and, consequently, can be put up without difficulty and may be readily removed, as occasion requires.

We claim:

A curtain fixture comprising top and bottom brackets, an arm supported by the said top-bracket, a chain hooked onto the said arm, and a latch connected with the lower end of the chain, said latch provided on opposite sides with lugs, said bottom-bracket 75 having side flanges formed with notches for the reception of said lugs.

In testimony whereof, we have signed this specification in the presence of two subscribing witnesses.

STEPHEN SIMON.
WILLIAM O'NEILL.

Witnesses:

FREDERIC C. EARLE,
MALCOLM P. NICHOLS.
